PLLC(57) **CLAIM**

The ornamental design for a stand for stylus pen, as shown and described.

DESCRIPTION

FIG. 1 is a front and top side perspective view of a stand for stylus pen, showing my new design;

FIG. 2 is a front view thereof and a back view is identical;

FIG. 3 is a left side view thereof and a right side view is identical;

FIG. 4 is a top view thereof;

FIG. 5 is a bottom view thereof;

FIG. 6 is a rear and bottom side perspective view thereof; and,

FIG. 7 is a sectional view thereof taken along line 7-7 of FIG. 4.

The long dash short dash broken lines and arrows shown in FIG. 4 are used to identify the sectional view and form no part of the claimed design. The evenly spaced broken lines in FIG. 7 represent hatching lines and form no part of the claimed design.
